UNITED STATES PATENT OFFICE.

HENRY JOSEPH ROUND, OF LONDON, ENGLAND, ASSIGNOR TO RADIO CORPORATION OF AMERICA, OF NEW YORK, N. Y., A CORPORATION OF DELAWARE.

ELECTRON-EMISSION DEVICE.

Application filed September 2, 1920, Serial No. 407,664, and in Great Britain September 3, 1919.

When a valve is employed for transmitting in wireless signaling, one end of the filament is connected through a circuit to the anode and in consequence when the power is such that the electronic emission current is comparable with the current employed for heating the filament the latter is unevenly heated owing to the fact that the emission current varies at different points of the filament.

According to this invention and in order to reduce the unevenness of the heating I connect to the filament at a number of points evenly spaced along it a number of resistances, the other ends of which are connected together and form the cathode terminal. These resistances must be sufficiently large to prevent portions of the filament being short circuited. By employing a large number of resistances the emission current may be divided approximately uniformly between the resistances and the heating of the filament may thus be made much more uniform.

The resistances and their common junction are preferably placed inside the valve so that only one additional seal is necessary.

My invention is illustrated by the accompanying diagram which shows a zig zag filament A having resistances B connected to it at various points, their other ends being connected to a lead C the middle point of which is connected through the usual form of circuit to the anode D.

Having now particularly described and ascertained the nature of my said invention and in what manner the same is to be performed, what I claim is:

1. In combination, a thermionic valve having filament and anode electrodes adapted to carry space currents, a circuit connected therebetween, a direct current source of heating current for the filament and a pair of resistances connected in said circuit for carrying the space currents to the filament, each having one end connected to a different point of the filament and their other ends connected to the said circuit.

2. In combination, a thermionic valve having filament and anode electrodes arranged to carry space currents in a circuit therebetween, a source of direct current connected to the filament for heating it and a pair of resistances connected in said circuit for carrying the space current to the filament, said resistances having a common point of connection and the other ends of each being

connected to different points of the filament and to said source.

3. In combination a thermionic valve having filament and anode electrodes arranged to carry space currents in a circuit therebetween, a source of direct current connected to the filament for heating it and a pair of resistances connected in said circuit for carrying the current to the filament, said resistances having a common point of connection and the other ends of each being connected to different points of the filament and to said source, and a source of space current connected between said common point and said anode.

4. In combination, a thermionic valve having filament and anode electrodes arranged to carry space current in a circuit therebetween, a source of direct current for heating said filament, a resistance connected to an intermediate point of said filament and a source of current having one terminal connected to said anode and the other terminal connected to both ends of the filament and also to said intermediate point through said resistance.

5. A thermionic valve comprising an enclosure, a filament and an anode, arranged to carry space current therebetween, a source of anode filament current and a plurality of resistances in said enclosure, adapted to be connected to the source of anode filament current, said resistances being connected to different points of the filament for carrying space current thereto.

6. A thermionic valve comprising an enclosure having a filament, an anode and a plurality of resistances therein connected to different points of the filament for distributing the anode-filament space current along the filament.

7. In a thermionic valve, the combination with a filament and an anode for said valve of a resistance means within the valve for distributing the anode filament space current along the filament.

8. In a thermionic valve, the combination with a filament and an anode for said valve of three or more resistances and means connecting together one end of each resistance, the other ends of the resistances being connected to different points on the filament.

9. In a thermionic valve, in combination, a filament and an anode for said valve, three or more resistances and means connecting to-

- gether one end of each resistance, the other ends of the resistances being connected to different points on the filament, and an evacuated envelope within which the aforesaid 5 elements are mounted.
10. In a thermionic valve, a combination with a filament and an anode for said valve mounted in an enclosure of three or more resistances, a lead connecting together one 10 end of each resistance and mounted in the enclosure, the other ends of the resistances being connected to different points of the filament.
11. In a thermionic valve, the combination 15 with a filament and an anode for said valve of three or more resistances of equal value and means connecting together one end of each resistance, the other ends of the resistances being connected to different points on the filament. 20
12. In a thermionic valve, in combination, a filament and an anode for said valve, three or more resistances of substantially equal value and means connecting together one end of each resistance, the other ends of the resistances being connected to different points on the filament, and an evacuated envelope within which the aforesaid elements are mounted. 25

HENRY JOSEPH ROUND.
